(57) **CLAIM**

The ornamental design for an tamper evident child resistant jar, as shown and described.

DESCRIPTION

FIG. 1 is a perspective view of an tamper evident child resistant jar showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof;

FIG. 8 is a bottom plan view thereof;

FIG. 9 is an open state diagram thereof;

FIG. 10 is another open state diagram thereof;

FIG. 11 is a perspective view of Component One;

FIG. 12 is a front elevation view of Component One;

FIG. 13 is a left side view of Component One;

FIG. 14 is a top plan view of Component One;

FIG. 15 is a bottom plan view of Component One;

FIG. 16 is a perspective view of Component Two;

FIG. 17 is a front elevation view of Component Two;

FIG. 18 is a top plan view of Component Two;

FIG. 19 is a bottom plan view of Component Two;

FIG. 20 is a perspective view of Component Three;

FIG. 21 is a front elevation view of Component Three;

FIG. 22 is a back elevation view of Component Three;

FIG. 23 is a left side view of Component Three;

FIG. 24 is a right side view of Component Three;

FIG. 25 is a top plan view of Component Three; and,

FIG. 26 is a bottom plan view of Component Three.

A back elevation view and a right side view of Component 1 are omitted due to the same with a front elevation view and a left side view of Component 1, respectively.

(Continued)

A back elevation view, a left side view and a left right side view of Component 2 are omitted due to the same with a front elevation view of Component 2.

The broken lines in the figures illustrate the portions of the design that form no part of the claimed design.
